UNITED STATES PATENT OFFICE

ERNEST B. NORMAN, OF NEW ORLEANS, LOUISIANA, ASSIGNOR TO RELIANCE MACHINE AND STAMPING WORKS, OF NEW ORLEANS, LOUISIANA, A CORPORATION OF LOUISIANA

PRESSURE GREASE GUN

Application filed September 15, 1930. Serial No. 482,017.

This invention relates to pressure grease guns of that type in which a socketed end of the grease gun is adapted to fit over and be coupled to a cylindrical nipple, having pins 5 extending from its sides and cooperating with under-shelving portions of the socketed end, to pull the latter forcibly into sealing contact with the end of the nipple when tightening movement is imparted to the socketed end.

The invention contemplates the provision of a pressure grease gun having a two-part socketed end or coupling, one part bearing against the end of the nipple and the other 15 adapted to engage the underside of the pins, the two parts being threaded together so that when the parts are relatively rotated in tightening direction, the one part presses up against the under-side of the pins, drawing 20 the other part down firmly against the end of the nipple.

To ensure that both parts of the socketed end shall not rotate together when it is attempted to impart relative rotation to said 25 parts, the inner part, that is to say, the part which is integral with the gun barrel and which makes sealing contact with the nipple end, is formed with slots fitting down over the pins, and since the outer part has the under-shelving ledge bearing up against the pins, it is necessary that this ledge have slots to 30 permit the pins to pass into the socketed end of the grease gun.

It is obvious that the slots in the two parts 35 of the socketed end must be in alignment when the gun is applied to the nipple, to permit passage of the pins and that the same slots must be in alignment when the grease gun is to be removed from the nipple.

One of the objects of the present invention 40 therefore, is to provide a stop on one of the threaded parts of the socketed end, and an abutment on the other part, said pin engaging said abutment when the two parts are 45 positioned with their slots in alignment.

Another object of the invention is to provide the inner part with a plurality of slots so 50 that the angular position of the inner part with respect to the nipple may be varied so as to obtain through the threaded connection

between said parts an initial adjustment of the distance between the face of the socketed end which engages the end of the nipple and the ledge which engages the underside of the pins to compensate for wear in the gun itself 55 or of the pin which the gun engages.

A further object of the invention is to provide for a selective shifting of the stop corresponding to the change in the angular position of the inner part of the socketed end, so 60 that the proper slots of the inner part are always in alignment with the slots in the outer part when the gun is to be positioned upon or withdrawn from the nipple.

Still another object of the invention is to 65 provide a stop which shall at the same time be the means for inseparably connecting the relatively movable parts of the socket portion of the grease gun.

Another object of the invention relates to 70 the plunger operating mechanism and proposes means for limiting the drop of the pawl ring when the plunger unit has been removed from the barrel so that the ring always remains in encompassing relation to said 75 plunger.

Other objects of the invention will appear as the following description of a preferred and practical embodiment thereof 80 proceeds.

In the drawings in which the same characters of reference have been used throughout the several figures to designate indentical parts:

Figure 1 is a side elevation of my improved pressure grease gun;

Figure 2 is a longitudinal section showing the relation of the socketed end to a nipple;

Figure 3 is a section taken along the line 90 3-3 of Figure 2;

Figure 4 is a section taken along the line 4-4 of Figure 2;

Figure 5 is a section taken along the line 95 5-5 of Figure 2; and

Figure 6 is a modified form of the invention in which the barrel of the gun is formed as an elbow.

Referring now in detail to the several figures and first advertizing to the general assembly shown in Figure 1, the numeral 1 100

represents the barrel of the grease gun which is integral with the inner socket member 2. A plunger 3 operates in the barrel and the grease which this particular gun is designed to extrude is of hard consistency, being furnished in the form of candles which are inserted into the top of the barrel after the plunger and its appurtenant operating mechanism has been removed. It will be obvious after the entire description has been unfolded that the inventive principle is not necessarily confined to the type of gun illustrated but that it is of general application to other forms of grease gun.

A handle 4 is pivoted to the plunger at 5, the handle extending beyond the pivotal connection 5 and being pivotally connected at 6 to a link 7 which in turn is pivotally connected at 8 to a pawl ring 9. The pawl ring 20 may be detained in any one of three positions by means of a detent 10 which operates within notches 11 and 12 and against the shoulder 13. The lowermost of these three positions is indicated in full lines and is the position in which the pawl ring is made to assume when the plunger is in its working phase. The upper broken line position of the pawl ring is that to which it is moved when the plunger is being retracted step by step while the middle position, also shown in broken lines, is that in which the pawl ring is inactive with regard to the barrel 1, in which position the plunger with its operating mechanism may be bodily withdrawn from the barrel for the purpose of introducing a fresh stick of grease. When the pawl ring is in the full line working position, it ratchets against the shoulders formed by the corrugations 14 on the gun barrel, said pawl ring acting as a fulcrum for the power applied to the handle 4 so that the plunger 3 is forced into the barrel with great leverage. When the pawl ring is moved to its oppositely inclined position it ratchets oppositely against the corrugations 14, the plunger being withdrawn step by step.

This construction is covered in the pending application of E. A. Dunlap Serial No. 472, 953, filed August 4, 1930, and the present improvement involves the additional shoulder or stop 15 which eventually comes into contact with the detent, but only when the plunger together with its operating mechanism has been removed entirely from the gun barrel. It will be noted from Figure 1 that the end of the plunger 3 is so positioned relative to the ring pawl that if the stop 15 were not present the ring pawl would fall beyond the end of the plunger necessitating that the plunger be again introduced into said ring pawl before the plunger is reinserted into the barrel. The stop 15 obviates this inconvenience by catching the ring pawl before it can descend far enough to go beyond the lower end of the plunger.

Referring to Figure 2 it will be observed that the pressure grease gun is used in connection with a nipple 16 having a plane face 17 and a pin 18 extending from said nipple on both sides. It will also be observed that the lower end of the grease gun barrel is formed with an enlargement 19 forming the inner part of the socketed end and being provided at its outer edge with a plurality of diametrically arranged pairs of slots, any opposite two of which slots may be slipped over the extending ends of the pin 18 so as to prevent the grease gun barrel rotating with respect to the nipple. Figure 2 shows that the inner part 19 of the socketed end is externally threaded and that an outer part 20 is provided, threading on the inner part and being provided with a handle 21 by which it may be turned in either direction. The outer part 20 has a ledge 22 extending beneath the ends of the pin 18 and in order for the pin to get into the channel formed between the inner and outer parts of the socketed ends, the ledge 22 is slotted as shown at 23 in Figure 4. When the inner and outer parts are so arranged that a pair of slots of the inner part are in registry with the slots of the outer part, the socketed end can be slipped over the pin 18 and down upon the nipple until the shoulder 20' engages the plane face 17 of the nipple. When the parts are in this position, the under-shelving ledge 22 is in a plane slightly below the lower surface of the pin 18 so that when the handle 21 is operated rotating the outer part 20, the slots in said outer part through which the pins travel when the device was placed upon the nipple, moves out of alignment with the pins and the ledge 22 comes beneath said pins and moves up into tight relation with said pins due to the screwing up of the part 20 upon the part 19. The pressure of the ledge against the under-side of the pin draws the shoulder 20' down to close sealing contact with the plane face of the nipple.

In order to ensure that the slots in the outer part and a pair of slots of the inner part are in alignment at the time of introducing or withdrawing the grease gun relatively to the nipple, a portion of the periphery of the outer part is cut away at the top as indicated at 24 in Figure 3, leaving an abrupt shoulder 25. A pin 26 is screwed or otherwise fixed relatively to the inner part, said pin being in the path of the shoulder 25 and being so related to a pair of slots at the bottom of the inner part that when the outer part has been rotated until the shoulder 25 comes into contact with the pin 26, the position of the parts is such that the pair of slots of the inner member engaging the pin 18 are in alignment with the pair of slots in the outer member. Consequently, before applying the grease gun to the nipple or before removing it, it is merely necessary to grasp the barrel and to turn the

outer part of the socketed end by means of the handle 21 until the pin 26 and the shoulder 25 are in contact.

The cutting away of the upper edge of the 5 outer member to form the depression 24, also forms a shoulder 27 on the opposite side of the pin 26 to that of the shoulder 25 so that in tightening the coupling, the shoulder 27 approaches the pin 26. If the grease gun is 10 somewhat worn, or if the lower sides of the pin 18 are much worn from use, it may be that the shoulder 27 may strike the pin 26 before tight engagement of the gun with the nipple has been effected. It therefore, becomes es- 15 sential to provide greater arcuate space between the shoulder 27 and pin 26 and this is accomplished by providing a circumferential series of sockets, threaded or otherwise furnished with pin retaining means, into which 20 sockets the pin may be successively transferred according to the degree of wear and the amplitude of the relative rotation of the parts necessary for the proper tightening of the grease gun. If upon attempting to tight- 25 en the coupling engagement of the grease gun with the nipple, the shoulder 27 abuts the pin 26 before a tight connection has been ef- fected, the pin 26 is transferred to the next 30 socket in a clockwise direction, that is to say, the socket 28. The outer part may then be rotated through an additional arc equal to the angle between the pin 26 and the shoulder 27 within which arc the tight relation of the parts may be obtained. If it is not, the pin 35 is transferred to still another socket in a clockwise direction. It is to be understood that it is not necessary to change the pin 26 frequently and consequently, a screw kerf 29 is found to be a practical and sufficient means 40 for effecting the withdrawal of the pin and its reinsertion into an adjacent socket.

The pin 26 also acts as means for holding the two parts of the socketed end of the grease gun in unitary relation, preventing 45 loss of the outer part together with the handle.

The operation of the invention has been de- 50 scribed step by step as the description pro- ceeded so that it is unnecessary to repeat the statement of operation at this point other than to emphasize the fact that the pressure of the ledge 22 upwardly against the under- side of the pin 18, draws the shoulder 20' down into firm, sealing contact with the 55 plane surface of the nipple so as to prevent any extrusion of grease into the socket, while the fact that there is total absence of ro- tation between the shoulder 20' and the coact- ing end of the nipple prevents wear of these 60 parts and ensures a long life both to the nip- ple and the gun.

The wear takes place solely at the upper 65 surface of the ledge 22 and on the lower side of the pin 18. By virtue of the adjusting feature above described, a fresh portion of

the ledge 22 is from time to time presented to the pin 18, so that the wear on the ledge 22 is minimized. Wear of the pin 18 is usually cured by replacing the entire nipple, al- though in an emergency the pin can be driven 70 out and turned so as to present a fresh sur- face at its under-side.

In Figure 6 a form of the invention is shown in which the barrel 1 is formed with an elbow 30 so that the operation of the plunger is at right angles to the axis of the 75 socketed end.

In other respects, this form of the invention is similar to that which above has been 80 described in detail.

While I have in the above invention endeavored to describe what I believe to be a preferred and practical form of my invention, it is to be understood that the details of construction as shown are merely by way of example and may be substituted by their 85 equivalents and that the scope of the invention is to be measured by the extensiveness of the appended claims.

What I claim is:

1. Coupling for attaching a grease gun to a nipple of that type comprising a cylindri- 90 cal body with a flat end normal to the axis of said body, with a grease conduit opening into said flat end, and with lateral projections below said flat end, said coupling comprising an inner member having an axial bore, formed as a socket with a peripheral flange and an internal shoulder surrounding said bore, the edge of said flange being pro- 95 vided with a series of indents for selectively receiving the lateral projections, an outer member screwing on said inner member and having an inwardly directed ledge at its free end extending over the ends of said indents, the latter being sufficiently deep to be out 100 of contact at their bottoms with said pro- jections when said ledge contacts with the flat end of said nipple, the side of said ledge adjacent the ends of said indents lying in a plane perpendicular to the axis of rotation of said outer member, and having projection- 105 admitting channels breaking its continuity and registrable selectively with said indents.

2. Coupling as claimed in claim 1, includ- 110 ing co-acting means on said inner and outer members acting as a stop to aline said chan- nels with certain of said indents, one of said co-acting members being adjustable to deter- 115 mine the selection of the indents into which said projections shall be introduced.

In testimony whereof I affix my signature.
ERNEST B. NORMAN.
